ENGINE STARTER GEARING

David L. Tobias, Elmira, N. Y., assignor to Bendix Aviation Corporation, a corporation of Delaware

Application September 20, 1951, Serial No. 247,443

5 Claims. (Cl. 74—7)

1

The present invention relates to engine starter gearing and more particularly to a drive of the automatically traversing type having novel means for preventing premature demesh of the drive pinion.

In starter gearing of the above type in which the demeshing of the drive pinion is controlled responsive to engine speed, it sometimes happens that sudden acceleration of the pinion by sporadic vigorous explosions of the engine may cause its speed to momentarily exceed the critical speed and cause demesh of the drive before the engine is reliably self-operative.

It is an object of the present invention to provide a novel engine starter drive of the so called "anti-kickout" type having means for preventing demesh of the drive during periods of rapid acceleration, even though the pinion momentarily rotates faster than the critical speed.

It is another object to provide such a device in which the speed-controlled device is in the form of a spring-pressed latch which is disengaged by centrifugal force, and the acceleration-controlled device is in the form of a detent opposing release of the latch.

Further objects and advantages will be apparent from the following description taken in connection with the accompanying drawing in which:

Fig. 1 is a side elevation partly broken away and in section of a preferred embodiment of the invention showing the parts in idle position;

Fig. 2 is an enlarged detail in section taken substantially on the line 2—2 of Fig. 1 showing the latch mechanism;

Fig. 3 is a detail similar to Fig. 2 showing the parts in cranking position;

Fig. 4 is a similar detail showing the parts in the positions assumed when the engine fires and accelerates the drive pinion;

Fig. 5 is a similar detail showing the parts as positioned during the demeshing movement of the drive.

In Fig. 1 of the drawing there is illustrated a power shaft 1 on which a sleeve 2 having a drive head 3 is fixedly mounted as by means of a cross pin 4. A driving overrunning clutch member 5 is slidably journaled on the sleeve 2 and yieldingly connected to the drive head 3 of the sleeve by means of a spring 6 the ends of which are connected to the drive head and clutch member by the anchor plates 7 and 8 respectively. The spring 6 is maintained under light initial compression by means of a lock ring 9 seated in a groove 11 in the sleeve and received by a counterbore 12 in the driving clutch member 5.

2

A screw shaft 13 is slidably journaled on the sleeve 2 and is provided with overrunning clutch teeth 14 adapted to cooperate with similar clutch teeth 15 on the clutch member 5. A stop ring 16 is mounted on the end of the sleeve 2 and is retained thereon by a lock ring 17. A light compression spring 18 is located between the stop ring 16 and the end of the screw shaft 13, and is operative to normally maintain the clutch teeth 14, 15 in engagement. A thrust washer 19 is preferably interposed between the clutch spring 18 and the end of the screw shaft.

A pinion 21 is slidably journaled on the power shaft 1 for movement into and out of mesh with an engine gear 22. A barrel member 23 is anchored at one end to the pinion as indicated at 24 and is provided at its other end with slots 25 adapted to receive lugs 26 extending radially from a control nut 27 threaded on the screw shaft 13, the control nut being retained in the barrel by a lock ring 28.

Means are provided for opposing the demeshing movement of the pinion when it is rotating below a predetermined critical speed. As here shown this means is in the form of a latch member 29 slidably mounted for radial movement in the control nut 27 against a compression spring 31, and arranged to drop into a notch 32 in the screw shaft when the pinion is moved into meshing position.

Means are provided for preventing disengagement of the latch 29 from the notch 32 by centrifugal force while the pinion and its associated parts are being accelerated by the engine gear. As shown in Fig. 2 this means is in the form of a detent 33 slidably mounted in the control nut 27 for tangential movement into and out of engagement with the latch 29. The detent 33 is located on the forward side of the latch 29 as respects the direction of rotation of the parts, as indicated by the arrow *a* and is normally maintained out of engagement with the latch by a spring 34. The latch 29 is formed with a shoulder 35 in such position that when the latch is moved into the notch 32 of the screw shaft, said shoulder is located radially inward from the path of the detent 33 as shown in Fig. 3, sudden acceleration of the pinion and control nut is thereby effective to move the detent 33 into engagement with the latch 29 above the shoulder 35 as shown in Figure 4, thereby opposing the releasing movement of the latch.

In operation, starting with the parts in the positions shown in Figs. 1 and 2, rotation of the power shaft 1 in the direction of the arrow *a* causes the control nut 27 to be traversed to the

left in Fig. 1 so as to mesh the pinion 21 with the engine gear 22, after which the latch 29 enters the notch 32 in the screw shaft so as to hold the pinion in mesh. The meshing movement of the control nut 27 is limited by the stop ring 16, after which rotation of the pinion is transmitted to the engine gear to crank the engine.

When the engine fires, the acceleration of the engine gear transmitted to the pinion causes the pinion, barrel and control nut to overrun the power shaft which would normally tend to cause the control nut to be traversed back toward idle position. This movement, however, is prevented by the engagement of the latch 29 in the notch 32 of the screw shaft so that the screw shaft is forced to rotate with the control nut, such rotation being permitted by the overrunning clutch connection 14, 15. If the initial explosions are vigorous, the rotation of the pinion and control nut may exceed the critical speed necessary to cause the latch 29 to move outward by centrifugal force and permit the parts to be traversed back to idle position. During the period of acceleration however, the inertia of the detent 33 causes it to compress the spring 34 and move into the position shown in Fig. 4 whereby the latch is maintained in engagement irrespective of the speed of rotation of the parts. When the engine becomes reliably self-operative so that its rotational speed does not fluctuate widely, the spring 34 moves the detent 33 out of engagement with the latch 29 which is thus permitted to move radially outward and allow the pinion and its associated parts to return to idle position.

Although but one embodiment of the invention has been shown and described in detail it will be understood that other embodiments are possible and changes may be made in the design and arrangement of the parts without departing from the spirit of the invention.

I claim:

1. In an engine starter drive, a power shaft, a pinion slidably journaled on the power shaft for movement into and out of mesh with an engine gear, means responsive to acceleration of the power shaft for traversing the pinion into mesh with the engine gear and then rotating the pinion to crank the engine, said means being operative to demesh the pinion when its speed exceeds that of the power shaft, means for preventing demeshing of the pinion below a predetermined critical speed, and means responsive to a predetermined rate of acceleration of the pinion for maintaining the effectiveness of said demesh-preventing means above said critical speed; including fur-

ther an overrunning clutch between the power shaft and the pinion-traversing means.

2. In an engine starter drive, a power shaft, a pinion slidably journaled on the power shaft for movement into and out of mesh with an engine gear, means responsive to acceleration of the power shaft for traversing the pinion into mesh with the engine gear and then rotating the pinion to crank the engine, said means being operative to demesh the pinion when its speed exceeds that of the power shaft, means for preventing demeshing of the pinion below a predetermined critical speed, and means responsive to a predetermined rate of acceleration of the pinion for maintaining the effectiveness of said demesh-preventing means above said critical speed; in which the demesh-preventing means is in the form of a centrifugally-released latch, and the means for maintaining the effectiveness of the latch is in the form of a tangentially movable detent engageable with the latch.

3. In an engine starter drive a power shaft, a screw shaft rotatably mounted thereon, yielding means connecting the screw shaft to rotate with the power shaft, a control nut on the screw shaft, a pinion slidably journaled on the power shaft for movement into and out of mesh with an engine gear, a barrel member connecting the control nut and pinion, a latch member mounted in the control nut for radial movement into and out of engagement with the screw shaft, and a detent mounted in the control nut for tangential movement into and out of engagement with the latch.

35 4. An engine starter drive as set forth in claim 3 including further a spring normally urging the latch into engagement with the screw shaft, and said screw shaft having a notch for receiving the end of the latch to oppose demeshing movement of the control nut.

40 5. An engine starter drive as set forth in claim 3 in which the detent is located on the forward side of the latch as respects rotation of the control nut and including further a spring normally holding the detent out of engagement with the latch.
